UNITED STATES PATENT OFFICE.

ODE DICK, OF WACO, TEXAS.

RAZOR WIPER AND LATHER RECEPTACLE.

Application filed January 25, 1928. Serial No. 249,298.

This invention relates to a new article of manufacture for use by barbers, and has particular reference to a device for use in wiping the lather from a razor during the act 5 of shaving and embodying a receptacle for receiving the lather as it is wiped from the razor.

In barber shops and the like, it is the common practice to place a piece of paper 10 on the customer's chest so as to be readily accessible for having the lather wiped thereon from the razor during the act of shaving. This practice, besides being unsanitary and incurring the liability of the 15 paper being displaced from the customer's chest and causing the lather to be smeared over anything which it may contact, requires the expenditure of considerable time in lifting the paper and holding it 20 in the hand during the wiping operation. Care is also necessary to properly wipe the lather from the razor to clean the latter and deposit the lather so that it will not be too 25 near the edge of the paper. Then too, there is the objection that the lather will run off of the flat piece of paper and soil the cloth which is placed over the customer's chest.

The primary object of the present invention, therefore, is to provide a device which 30 need only be held still while the razor is wiped thereon, and which embodies a cup into which the lather is wiped for being prevented from running onto the cloth.

A further object is to provide a razor wiper 35 and lather cup which may be readily kept clean and which will effectively wipe the lather from the razor.

Further objects are to provide a device 40 of the above kind which may be cheaply and easily manufactured, which will not cause discomfort to the customer, and which embodies safe and efficient means for preventing accidental displacement thereof from the customer's chest.

Other objects will become apparent as the 45 nature of the invention is better understood, and the same consists in the novel form, combination and arrangement of parts hereinafter more fully described, shown in the accompanying drawing and claimed.

In the drawing:

Figure 1 is a top plan view of a razor wiper and lather receptacle constructed in accordance with the present invention.

Figure 2 is a transverse section on line 50 2-2 of Figure 1.

Figure 3 is an enlarged bottom plan view of a modified form of the invention, partly broken away and in section.

Figure 4 is a fragmentary section on line 60 4-4 of Figure 3, and

Figure 5 is a central transverse section of the device shown in Figure 3, with one of the pin fasteners shown as engaged in the cloth to prevent accidental displacement of 65 the device.

Referring to the drawing in detail, the present invention comprises a shallow cup or tray consisting of a single piece of soft rubber and having a short preferably cylindrical side wall 5 which tapers upwardly to form a yieldable upper edge 6 having a flat top surface 7 over which the blade of the razor is drawn to wipe the hair and lather therefrom. The tray has a thin flexible bottom wall 8, and extending downwardly and outwardly from the side wall 5 to a plane below the bottom wall 8 is a thin yieldable supporting flange 9 which is of continuous or annular form and flares in a downward direction to have its lower edge contact the customer's chest or body and hold the bottom of the tray elevated or out of contact therewith. In this way, the device will not cause discomfort and the flange 9 will yield 80 to the pressure of the razor when the latter is wiped. Moreover, should the flange 9 be sufficiently flattened as to cause the bottom wall 8 to contact the chest, said bottom wall will readily yield and further insure against 85 discomfort. The lower major portion of the side wall 5 is relatively thick and stiff to permit grasping thereof without causing material distortion of the same when steady- 90 ing the device during the razor wiping 95 operation.

In use, the side of the razor blade is pressed against the surface 7 and the blade is then drawn outwardly so that the lather is wiped from the blade into the tray. As the edge 6 is yieldable, it will conform to the hollowed shape of the blade to effectively 100 clean the latter.

The form of the invention shown in Figures 3 to 5 inclusive is the same as that of Figures 1 and 2, except that a plurality of pin fasteners 10 are provided on the inside of the flange 9 and at suitably spaced points so as to normally project inwardly from said flange adjacent to but wholly above the lower edge of the flange, as shown in Figure 4. The pins or pin fasteners 10 have their 105 110

heads embedded and vulcanized in the flange 9, and such heads are preferably in the nature of cross bars 11. By pressing down on the flange 9 adjacent one of the pins 10, the latter may be forced to project downwardly slightly below the adjacent portion of the flange as shown in Fig. 5, at 12, to engage in the cloth 13 which is placed over the customer's chest. In this way, the device will be effectively prevented from being accidentally displaced when in use.

Minor changes may be made without departing from the spirit and scope of the invention as claimed.

15 What I claim as new is:

1. As a new article of manufacture, a soft rubber tray having a short cylindrical side wall which tapers upwardly to form a yieldable upper edge having a flat top surface over which a razor blade may be drawn to have the lather wiped therefrom into the tray, said tray having an integral yieldable supporting flange of continuous form projecting outwardly and downwardly therefrom with its lower edge in a plane below the bottom of the tray.

2. As a new article of manufacture, a soft rubber tray having a yieldable upper edge over which a razor blade may be drawn to have the lather wiped therefrom into the tray, said tray having an integral yieldable supporting flange of continuous form projecting outwardly and downwardly therefrom with its lower edge in a plane below the bottom of the tray, and means carried by the supporting flange engageable with the barber's cloth to hold the tray against accidental displacement.

3. As a new article of manufacture, a soft rubber tray having a yieldable upper edge over which a razor blade may be drawn to have the lather wiped therefrom into the tray, said tray having an integral yieldable supporting flange of continuous form projecting outwardly and downwardly there-

from with its lower edge in a plane below the bottom of the tray, means carried by the supporting flange engageable with the barber's cloth to hold the tray against accidental displacement, said last named means embodying a pin fastener embedded in and projecting inwardly from the flange.

4. As a new article of manufacture, a soft rubber tray having a yieldable upper edge over which a razor blade may be drawn to have the lather wiped therefrom into the tray, said tray having an integral yieldable supporting flange of continuous form projecting outwardly and downwardly therefrom with its lower edge in a plane below the bottom of the tray, means carried by the supporting flange engageable with the barber's cloth to hold the tray against accidental displacement, said last named means embodying a pin fastener embedded in and projecting inwardly from the flange adjacent to but normally wholly above the lower edge of the latter.

5. As a new article of manufacture, a soft rubber tray having a yieldable upper edge over which a razor blade may be drawn to have the lather wiped therefrom into the tray, said tray having an integral yieldable supporting flange of continuous form projecting outwardly and downwardly therefrom with its lower edge in a plane below the bottom of the tray, means carried by the supporting flange engageable with the barber's cloth to hold the tray against accidental displacement, said last named means embodying a pin fastener embedded in and projecting inwardly from the flange adjacent to but normally wholly above the lower edge of the latter, the portion of the flange adjacent the pin fastener being yieldable to permit the latter to be projected downwardly to engage the cloth.

In testimony whereof I affix my signature.

ODE DICK.
